CONDUCTOR-RETRIEVING DEVICE FOR VACUUM CLEANERS.

Application filed February 25, 1925. Serial No. 11,558.

Our invention relates to electrically operated vacuum cleaners and particularly, although not necessarily, to portable vacuum cleaners as used for domestic purposes.

- 5 It is a purpose of our invention to provide a device capable of being incorporated in a vacuum cleaner of any conventional form for retrieving the electrical conducting cord used in supplying current to the motor of the 10 cleaner from a wall plug whereby, the length of the cord can be varied at will as the cleaner is moved about a room and in such manner as to prevent accumulation of slack cord and the disadvantages attendant thereto.
- 15 It is also a purpose of our invention to provide a conductor retrieving device of extremely simple, inexpensive and durable construction which can be associated with the guiding or operating arm of a vacuum cleaner 20 without radical modification of the arm structure and in such relation as to permit the convenient control of the device and the supply of current to the motor of the cleaner through such device.
- 25 We will describe only one form of conductor retrieving device embodying our invention and will then point out the novel features thereof in claims.

In the accompanying drawings:

- 30 Figure 1 is a view showing in perspective one form of conductor retrieving device embodying our invention in applied position to a vacuum cleaner.
- 35 Figure 2 is an enlarged longitudinal sectional view of the retrieving device shown in Figure 1.
- 40 Figure 3 is a fragmentary sectional view similar to Figure 2 showing the reel in released position.
- 45 Figure 4 is a transverse sectional view taken on the line 4-4 of Figure 3.

Referring specifically to the drawings in which similar reference characters refer to similar parts in each of the views, our invention in its present embodiment is shown associated with the conventional guiding or operating arm 15 of a vacuum cleaner, such arm being of tubular form and pivotally associated with the body of the cleaner for 50 moving the latter over the floor. As shown in Figure 2, a casing or housing is secured upon the upper end of the arm 15, and this casing comprises a lower section 16 secured to the arm 15 by means of a clamp 17, and an 55 upper section 18 threadedly connected to the

lower section and provided with a handle 19 adapted to be gripped by the operator when manipulating the vacuum cleaner. Secured to the lower inner face of the bottom section 16 is a plate 20 of insulating material, while 60 secured to the upper section 18 is another plate 21 of insulating material. Between these plates a reel formed of insulating material is arranged, the reel containing a hub 22 and flanges 23 on the ends of the hub. 65 This reel is fixed by means of a set screw 24 to a shaft 25 formed of conducting material and mounted for rotational and longitudinal movements within the plates 20 and 21 and the arm 15.

70 As clearly shown in Figure 2, the lower end of the shaft 25 is slidably and rotatably fitted in a tube 26 of conducting material fixed within a plug 27 of insulating material, the latter being threadedly fitted in the lower 75 end of the arm 15. The upper end of the shaft 25 projects upwardly from the plate 21 and through a leaf spring 28. Fixed to the shaft above the spring 28 is a collar 29 against which the spring bears for normally 80 urging the shaft upwardly so that its upper end is yieldingly retained in engagement with an operating plug 30 of insulating material 85 slidably mounted in a socket 31 formed in the casing section 18. The upward or outward movement of the operating plug is limited by means of a flange 32 formed on the inner end of the plug.

90 A sleeve 33 of insulating material surrounds the shaft 25 to insulate the latter from a metallic tubular shaft 34 extending into and fixed to the hub 22 of the reel. This shaft 34 carries a collar 35 to which the lower end of a spring 36 is fixed, the upper end of the spring being secured in the plate 20. 95 This spring 36 constitutes means for rotating the reel to effect winding of electrical conductors thereon, such conductors in the present instance comprising two wires 37 and 38 which are extended through a suitable 100 opening formed in the casing section 16, and in which opening is secured a collar 39 of insulating material. As shown in Figure 2, the wires 37 and 38 are secured to and electrically connected with conducting rings 40 and 41, respectively, secured to the opposite 105 ends of the hub 22, the ring 40 being engaged by a spring contact arm 42 secured to the plate 21 and electrically connected to a button switch 43 by a wire 44. A wire 45 electric- 110

cally connects the switch with the spring 28, and the latter being in contact with the shaft 25, the shaft serves to conduct current downwardly through the arm 15 to the conducting tube 26. From the tube 26, a wire (not shown) is extended to one brush of the motor as will be understood. The ring 41 is in contact with the metallic shaft 34, and the latter is in sliding contact with a contact arm 10 46 secured to the inner end of the plug 27 and connected to a wire 47 which extends through the plug for connection with the other brush of the motor. A second arm 48 is secured to the plug 27 to co-operate with 15 the arm 46 in centering the shaft within the arm 15, as will be understood.

In practice, the reel is rotated to wind the conductors or wires 37 and 38 upon the hub 22 and in such manner as to place the spring 20 36 under tension, it being understood that the winding of the spring in this manner is effected prior to the complete assembling of the device. The reel is normally held against rotation under the action of the spring 36 25 by virtue of the fact that it is urged upwardly to the position shown in Figure 2 by the spring 28, the spring acting through the shaft 25 so as to maintain the flange 23 in contact with the plate 21 with sufficient pressure to 30 prevent movement of the flange and thereby secure the reel against rotation. In this manner the plate 21 functions as a braking element.

In the use of the vacuum cleaner, the conductors 37 and 38 are of course connected to 35 a plug 49 (Figure 1), the latter being inserted in a suitable wall socket. As the vacuum cleaner is moved about the floor it is of course necessary that the conductors be varied in 40 length, and when it is desired to increase the length of the conductors, that is to say to unwind the latter from the reel, the plug 30 is positioned inwardly thereby flexing the spring 28 to permit lowering of the shaft 25 45 whereby the reel will gravitate to the released position shown in Figure 3 thus moving flange 23 out of contact with the plate 21. In this position of the reel, it is free to rotate so that by pulling the conductors outwardly 50 from the casing they will be unwound from the reel to the extent desired. Immediately following, the plug 30 is released thus allowing the spring 28 to return the reel into engagement with the plate 21 so as to secure the reel against rotation in either direction.

If it is desired to shorten the length of the conductors, in other words, to re-wind the latter upon the reel, it is only necessary to move the reel to the released position shown 60 in Figure 3 whereupon the spring 36 will act to rotate the reel in such direction as to re-wind the conductors thereon and thus take up any slack between the reel and the plug 49.

From the previous tracing of the conduct- 65 ing path of the current from the wires 37

and 38 to the motor of the vacuum cleaner, it will be clear that the switch 43 can be manually operated to control the supply of current to the motor. Both the switch 43 and the plug 30 are within easy reach of the 70 hand of the operator gripping the handle 19 so that the operation of the retrieving device and the energizing of the motor can be controlled without removing the hand from the handle. 75

Although we have herein shown and described only one form of retrieving device embodying our invention, it is to be understood that various changes and modifications may be made herein without departing from the 80 spirit of the invention and the spirit and scope of the appended claims.

We claim:

1. A retrieving device of the character described comprising a reel, means for rotating the reel in one direction to cause winding of flexible conductors thereon, a braking element, means for supporting the reel for bodily movement to engage or disengage the braking element, yieldable means for urging the reel into engagement with the braking element, and manually operable means for positively moving the reel out of engagement with the braking element whereby the first means will respond to rotate the reel. 95

2. A retrieving device of the character described comprising a braking element, a reel, a rotatably and slidably mounted shaft fixed to the reel, a spring associated with the shaft for normally urging the reel to a position in 100 which it engages the braking element to prevent rotation of the reel, a spring associated with the reel for rotating the latter in one direction when the reel is out of engagement with the braking element, and a manually 105 operable member engageable with the shaft for moving the latter against the action of said spring to move the reel out of engagement with the braking element.

3. A retrieving device of the character described comprising in combination with a tubular arm, a casing secured to the arm, a braking element within the casing, a reel within the casing, a plug in the arm, a shaft extending through and fixed to the reel and 110 mounted for rotation and longitudinal movement in the braking element and plug, a collar fixed to the shaft, a spring engaging the collar to normally urge the shaft upwardly and the reel into engagement with the braking element, a tubular shaft surrounding the first shaft and fixed to said reel, a spring associated with the tubular shaft for normally 115 urging the tubular shaft and consequently the reel in one direction, said spring capable of being wound upon rotation of the reel in the opposite direction, and manually operable means for moving the first shaft against the action of the first spring to cause said reel to 120

disengage the braking element in order to 125 130

allow the latter to respond to the action of the second spring and to permit rotation of the reel to place said spring under tension.

4. A retrieving device of the character described comprising a braking element, a reel, a rotatably and slidably mounted shaft fixed to the reel, a collar fixed to the shaft, a spring engaging the collar to normally urge the shaft and hence the reel to a position wherein

10 the reel has braking engagement with the braking element, a spring associated with the

reel for rotating the latter in one direction when the reel is out of engagement with the braking element, and a manually operable member mounted for sliding movement axially of the shaft and engaging an end of the shaft, for moving the shaft longitudinally against the action of said spring to move the reel out of engagement with the braking element.
